UNITED STATES PATENT OFFICE

ALFONS KRAUSE, OF BRESLAU-CAWALLEN, GIESCHE-SIEDLUNG, GERMANY, ASSIGNOR
TO AMERICAN GLANZSTOFF CORPORATION, OF NEW YORK, N. Y., A CORPORATION
OF DELAWARE

ARTIFICIAL SILK SPINNING MACHINE ATTACHMENT

Application filed October 27, 1931, Serial No. 571,474, and in Germany February 18, 1931.

This invention relates to an improvement in spinning machines.

One object of this invention is to provide a suitable attachment to be used on spinning machines which will collect the yarn during the doffing of the spinning pots.

Another object of this invention is to provide a suitable attachment which may readily be moved into operative positions 10 when the spinning pots are being changed.

These and other objects of this invention will become more apparent from a perusal of the following description and a study of the drawing in which:

15 Figure 1 is a diagrammatic view of a portion of an artificial silk spinning machine showing the attachment in operative position, and

20 Figure 2 is a view showing a modified form of attachment.

In the spinning of artificial and kindred threads and filaments, the threads are spun into a suitable coagulating solution and passed over suitable guiding and stretching 25 means to a rotating spinning pot where they are collected. When the pot is filled it is necessary to remove it and place another one in position. Since, because of the nature 30 of the spinning process, it is very inefficient, if not impossible, to stop the flow of the spinning solution into the coagulating medium, means are usually provided to collect the freshly spun thread during the changing of the spinning pot, or what is generally 35 known as the doffing period. Heretofore the thread has been cut and the end thereof wound on a spare roller. This method was extremely dissatisfactory since the thread collected on the spare roller was not only 40 worthless but rendered the apparatus unsightly and dirty.

According to this invention, the thread 45 —10— emerging from the coagulating bath (not shown) is passed over a take-up roller —11— and is led downwardly through the spinning funnel —12— into a spinning pot (not shown). Positioned adjacent the take-up roller and extending downwardly along the machine is protective wall or guard 50 —13— made of lead or other suitable mate-

rial. A gutter —14— is located beneath the take-up roller to receive the liquids which are brought to the take-up roller by the freshly spun thread.

The attachment comprises a horizontally 55 positioned platform or table —15—, made preferably of sheet aluminium and is provided at one end with a vertically extending member terminating in a hook —16— which fits over one side of the gutter. During 60 the normal operation of the spinning machine, the attachment is placed in inoperative position and the thread is collected in the spinning pot. When the latter becomes filled, the thread is cut between the 65 spinning funnel and take-up roller, and the attachment is moved into position so that the thread can accumulate during the exchange of an empty spinning pot for the one filled with thread. After the empty pot 70 is in position the thread is again cut and the attachment moved out of the way. The end of the thread is inserted into the spinning funnel and the normal operation of the machine continues. The thread collected 75 on the attachment is thus clean and has an absolutely even denier corresponding to the rest of the artificial silk. This thread may readily be collected, washed and used for schappe.

In Figure 2 there is shown a modified form of attachment in which the member extending vertically from the table or platform —15— is provided with a bracket —17— carrying a pintle on which is pivotally mounted the movable arm 18 of a clamp —19—, the vertically extending member forming the fixed arm thereof. The movable arm is pressed against the fixed arm by means of the spring —20—. By 80 this construction the attachment may be shifted along the lower end —21— of the protective wall or guard —13—. The use of this attachment is similar to that shown in Figure 1.

From the above description it will be seen that there has been provided a simple and efficient attachment which may readily be moved in operative position; and which will collect the thread during the doffing 95 100

period. This thread, so collected, will not be waste, as has heretofore been the case, but may be used for schappe.

Although the invention has been described with reference to the specific embodiment disclosed, it is to be understood that the invention is not specifically limited thereto, but may be modified in many details without departing from the spirit of the invention or the scope of the appended claims.

What is claimed is:

- 15 1. A machine for spinning thread having a take-up roller, a gutter located therebeneath, a guide means, a platform located between said take-up roller and guide means, movably secured to said gutter and adapted to receive the thread during the doffing operation.
- 20 2. A machine for spinning thread having a take-up roller, a gutter located therebeneath, a guide-means, a platform located between said take-up roller and guide means, and adapted to receive the thread during the doffing operation.
- 25 3. A machine for spinning thread including a take-up roller, a guide means located at a distance therefrom and a vertically extending protective member, a platform, vertically located between said take-up roller and guide-means, and movably secured to said protective member and adapted to receive the thread during the doffing operation.

In testimony whereof I affix my signature.
ALFONS KRAUSE.
